UNITED STATES PATENT OFFICE.

JAMES L. COFFIELD, OF DAYTON, OHIO.

GEARING FOR WASHING-MACHINES.

1,270,379.

Specification of Letters Patent. Patented June 25, 1918.

Application filed October 9, 1917. Serial No. 195,631.

To all whom it may concern:

Be it known that I, JAMES L. COFFIELD, a citizen of the United States, residing at Dayton, in the county of Montgomery and State 5 of Ohio, have invented certain new and useful Improvements in Gearing for Washing-Machines, of which the following is a specification.

This invention relates to a new and useful 10 form and arrangement of driving gear for washing machines, and to the washing cylinder or clothes receptacle. The object of the invention is to provide a gearing which is simplified and compact in its arrangement, 15 it being essential to concentrate the gearing as compactly as possible to enhance the appearance of the machine as well as to simplify details. In carrying out this object and purpose one of the side frames is especially 20 constructed with a view to locating the reduction gear on the inside of the frame and closely adjacent thereto while the power transmission shaft and the gears therewith associated are located on the outside of the 25 frame closely adjacent thereto. This arrangement of the driving gear avoids any cumbersome aspects and enhances the appearance of the washing machine as a whole by avoiding any unsymmetrical protuber- 30 ances or outlying elements and thereby renders the machine satisfactory, both as to efficiency and appearance. The mounting of the driving mechanism wholly on one of the side frames has decided advantages. 35 This side frame holds all the working parts in true alinement, and the wear is therefore reduced to a minimum and efficiency is greatly enhanced. The operating mechanism constructed and arranged in this way 40 is easily assembled as a unit on one side frame. This facilitates the machining and assembling in the manufacture of the machine and provides for an easy handling thereafter, the removal of the working parts 45 and the replacement of parts in case of wear being comparatively easy owing to the entire driving gear, being located on one side frame as before stated.

Preceding a detailed description of the 50 invention, reference in general terms is made to the accompanying drawings, of which Figure 1 is a side elevation of a washing machine equipped and constructed in accordance with the improvements embodied in my 55 invention. Fig. 2 is a front elevation thereof. Fig. 3 is a fragmentary and some-

what enlarged section of a portion of the side frame and the driving gear mounted thereon, including the reduction gear which lies on the inner side of the frame and the 60 power transmission gear which lies on the outer side of said frame, both being closely adjacent to the frame. Fig. 4 is a cross sectional view of the washing cylinder which is driven through means of said gearing, and 65 Fig. 5 is an elevation of the end of said washing cylinder with which the driving gear is connected.

In a more particular description of the invention similar reference characters are 70 employed to designate corresponding parts both in the description and the drawings.

The supporting frame of the machine is of an open work character consisting of side frame members 1 and 2 which are united by 75 suitable cross frame members 3, 4 and 5, the whole being designed to be light and rigid as well as symmetrical in appearance. The clothes receptacle consists of a cylinder 6, the journals 7 of which have bearings in 80 corresponding portions of the side frame members 1 and 2, the ends of said cylinder having attached thereto spiders or frames 8 from which the journals 7 project in reaching their bearings. The interior of the cylinder 6 is provided with a longitudinal rib 9 which forms an obstruction or barrier, the effect of which is to throw the clothes from one side to the other into the suds as the cylinder 6 is oscillated. This rib or obstruction 85 is essentially of a rounded form and devoid of sharp edges in order to avoid injuring the clothes during the operation and to avoid tying or knotting the clothes as 90 they are moved over the projection. The rib 9 being of the form or contour shown in the drawings has the effect of throwing the clothes into the suds from one side to the other in a more open or separated condition 95 which is highly desirable both for the reason that the clothes are prevented from being torn or injured during the operation of washing and are maintained in a more open condition. There are also provided on the 100 interior of the cylinder 6 a series of longitudinal ribs 10 of substantially smaller form, but of rounded form also, these ribs being designed to strengthen or brace the cylinder. A door 11 is provided at the top of the cylinder 6 with a suitable handle 12 by which 110 it is removed and replaced. The side frame member 2 is more especially constructed with

a view to supporting the driving mechanism which is compactly distributed on both sides thereof. The motor 13 is located on the inner side of the frame member 2 by means 5 of a suitable bracket 14 which is in turn supported on the cross frame members 4 and 5. The shaft of the motor carries a pulley 15 which drives a belt 16 through which power is transmitted to a larger pulley 17, 10 the journal 18 of which is provided with a bearing located also on the inner side of the frame member 2 in a skeleton housing 19 which is a part of the side frame construction. An angular lever 20 is fulcrumed at 15 21 on the inner side of the frame member 2 which carries a belt tightener 22 on one arm engaging the belt 16 and a spring 23 is connected to the other arm of said lever, the tension of which maintains the tightener 22 against the belt 16 with sufficient pressure 20 to drive the pulley 17. Any momentary relaxation of the belt tightener interrupts the transmission of the power from the motor. The journal or stud shaft 18 of the pulley 17 25 carries a small gear or pinion 24 which meshes with a larger gear 25, both gears 24 and 25 being positioned on the inferior of the offset or skeleton frame 19 or within the confines of the side frame 2. The stud shaft 26 of the gear 25 is journaled in a bearing 27 which extends from the skeleton frame 19 and carries a bevel gear 28, through which an upright transmission shaft 30 is driven, there being a similar gear 29 on the lower 30 end of said shaft 30 which is in mesh with the gear at 28. The shaft 30, it will be observed, lies relatively close to the side frame 2 and on the outer side thereof, being supported in a bearing 31 on the skeleton frame 40 19 at its lower end and in a bearing 32 projecting from the side frame 2 at its upper end. The said shaft 30 carries at its upper end a bevel gear 33 having an extension 34 which lies in the bearing 32 and is provided 45 on its upper end with a clutch member 35. The gear 29 is fixed to the shaft 30, but gear 33 is loose upon said shaft 30. The shaft 30 extends upwardly and a clutch member 36 which co-operates with the clutch member 50 35 is mounted on said shaft 30. The clutch member 36 has slideable movement on the said shaft 30, but rotates therewith by being splined thereto. The clutch member 36 is operated by a clutch shifter consisting of a 55 yoke 37 which spans the body of the clutch member 36 and is provided with pins 38 which enter a peripheral groove 39 in the body of the clutch member 36. The yoke 37 is pivoted to the side frame at 40 and extended therefrom is an operating lever 41 through which the shiftable clutch member 36 is operated to release or engage the clutch member 35. When the clutch member 35 is thus engaged the gear 33 is caused to rotate 60 with the shaft 30 and to drive the washing cylinder 6. When the clutch members are released as in Fig. 3, the operation of the washing cylinder ceases. The gear 33 meshes with a similar bevel gear 42 on a short or stud shaft 43 which is journaled in a bearing provided in an adjacent part of the side frame 2. The connection between the shaft 43 and the washing cylinder 6 consists of a crank 44 one end of which is fixed to the shaft 43, and a connecting rod 45 one 70 end of which is pivoted to the crank 44 and the other end of which is connected by a pivot 46 to a portion of the spider 8 on one end of the washing cylinder. It will be seen that as the gear 42 rotates an oscillatory movement is imparted to the cylinder which causes the clothes therein to be thrown back and forth from one side to the other of the cylinder. What may be termed a shock absorber is provided for the shaft 43 to prevent sudden jerks being imparted to the cylinder or an irregular movement. This device consists of projections 47 extending from the base of the gear 42 or fixed to the shaft 43 on the outside of the frame 2. These projections 47 are in the form of wipers which engage during the rotation of the gear, the concaved surface 48 of an arm 49. The arm 49 is pivoted to the outside of the frame 2 at 50 and the outer end of said arm has an opening therein which receives a rod 51 which is secured to the frame 2 between lugs 52. Arranged between the lugs 52 are upper and lower coil springs 53 which provide cushions or a means of yielding resistance to the arm 49 as the gear 42 rotates and the wipers or projections 47 engage the concaved surface 48 of said arm. The machine in its entirety is supported upon suitable casters 54. The several gears together 105 with the clutch which are on the outer side of the frame 2 are suitably inclosed by caps which may be conveniently united to the side frame 2. These caps have been omitted from the drawings in order that the gearing 110 may not be obscured, but it will be understood that the gearing as shown in Fig. 1 is all concealed within these inclosing caps and the appearance of the machine is greatly enhanced thereby, there being no visible 115 moving part appearing on the outside of the machine. I have, in connection with my improved washing machine gearing, shown an electric motor 13 as the power furnishing element. It will, however, be understood that other forms of power generators may be employed without departing from the essential features of my invention as set forth in the preceding part of this specification. The upright shaft 30 is extended 120 up beyond the washing machine proper in order to utilize the same to drive the rollers of a wringer. The wringer is no part of the present invention and need be referred to briefly as consisting of a frame 55 having 130

the usual wringer rollers 56 and 57, the latter roller being driven from the shaft 30 through a common form of gearing which is inclosed in a gear box 58 and from which 5 a shaft 59 is driven, the latter shaft being suitably connected with the wringer roller 57. The wringer is mounted upon a swinging support 60 which may be swung over and to one side of the washing machine as is 10 usual in the case of swinging wringer supports.

Having described my invention, I claim:

1. In an improved gearing for washing machines, a frame, a clothes receptacle 15 mounted therein, one side of said frame having provision for supporting a reduction gear on the inner side thereof, a reduction gear so mounted on the inner side of said side frame, an upright shaft supported in 20 bearings immediately upon the outer side of said side frame, driving gears interposed between said upright shaft and the reduction gears in bearings on said side frame, a clutch-controlled gear mounted in bearings 25 on said side frame and arranged to transmit the power from said upright shaft, a transmission gear mounted in a bearing in said side frame and meshing with said clutch-controlled gear, and a suitable connection be- 30 tween said transmission gear and the clothes receptacle for imparting movement to said clothes receptacle.

2. In a gearing for washing machines, a frame consisting of two side members and 35 suitable cross braces therefor, a clothes receptacle pivotally mounted in said frame, one of said side frame members being provided with stud shafts, gears mounted on the inside of said side frame member on two of 40 said stud shafts, an upright shaft mounted in bearings on the outside of said side frame member and driven from the gears on the inside of said side frame member, a gear mounted upon another of said stud shafts 45 and driven from said upright shaft, and a drying connection between said last-named gear and the clothes receptacle, said driving connection being arranged on the inner side of said side frame member.

3. In a gearing for washing machines, the combination of a supporting frame including two side members, three stud shafts mounted in bearings provided in one of said side frame members, a washing cylinder sup- 55 ported by said frame, initial driving gears supported on two of said stud shafts on the inside of said side frame member, an upright driving shaft mounted in bearings on the outside of said side frame member and 60 driven from said initial gears, a transmission gear mounted on the other of said stud shafts and driven from said upright shaft, and a connection between said last-named stud shaft and the washing receptacle for 65 imparting motion to the latter.

4. An improved gearing for washing machines, comprising side frame members, one of said side frame members being provided with a plurality of stud shafts, a clothes receptacle mounted in said side frame members, driving reduction gears mounted on two of said stud shafts on the inside of said side frame member, a horizontal transmission gear mounted on one of said stud shafts on the outer side of said side frame member and 70 in proximity thereto, an upright transmission shaft provided with upper and lower bearings on the outer side of said side frame member, a gear on the lower portion thereof in mesh with said horizontal gear, a 80 transmission gear and clutch on the upper portion of said upright shaft, a third stud shaft mounted in said side frame member, a second horizontal transmission gear mounted on said last-named stud shaft on the outside of said side frame member and meshing with the transmission gear on the upper portion of said upright shaft, and a 85 crank and connecting rod connected to said last-named stud shaft on the inside of said 90 side frame member and to the washing receptacle, and means for driving said reduction gears.

5. In a gearing of the character specified, a supporting frame including two side 95 frame members, a series of stud shafts mounted in bearings in one of said side frame members and two of which are in vertical alinement, a washing cylinder mounted in said supporting frame, reduction driving gears mounted on two of said stud shafts on the inside of said side frame member, a crank and connecting rod mounted on one of the vertically alined stud shafts and connected to said washing cylinder, an 100 upright transmission shaft mounted in bearings projected from the outer side of said side frame member and geared respectively to the stud shaft supporting one of the reduction gears, and the stud shaft to which 105 said crank and connecting rod are connected.

6. A washing cylinder, a supporting frame comprising side frame members one of which is constructed and arranged to wholly support the driving mechanism thereof, driving mechanism comprising reduction gears mounted on the interior of said side frame member, an upright transmission shaft mounted in bearings on the exterior of said side frame member, said shaft being operatively connected respectively to said reduction gears and to said washing cylinder, a gear on said upright shaft connecting it with the washing cylinder and being freely rotatable on said upright shaft, and clutch 115 devices on said upright shaft connecting said gear with said shaft.

7. A supporting frame comprising two side members, one of said side members being provided with horizontally disposed 120

125

130

- 4
- bearings and a less number of vertically disposed bearings; a washing cylinder mounted between said side frame members, stud shafts mounted in said horizontal bearings, 5 reduction driving gears mounted on the inside of said side frame member on two of said stud shafts, an upright transmission shaft mounted on the exterior side of said side frame in two of the vertical bearings 10 thereof, said upright shaft being geared to one of the said two stud shafts, a loose gear on said upright transmission shaft, a gear on another of said stud shafts in mesh with said loose gear, a crank connected to said last- 15 named stud shaft and to the washing cylinder, and a clutch connected with said upright shaft and adapted to connect said loose gear with the upright shaft and to disconnect it therefrom.
- 20 8. In a driving gear for washing machines, the combination of an oscillating clothes receptacle, a frame supporting said clothes receptacle including two side frame members, driving means, and a wringer supporting member, said driving means and wringer supporting member being mounted wholly on one of the side frame members and removable as a unit therewith.
- 25 9. In a driving gear for washing machines, an oscillating clothes container, side

frame members in which it is mounted, a main driving shaft, an upright shaft geared thereto, connections between the upright shaft and the clothes container for imparting an oscillating movement to the latter 35 from the rotary movement of the driving shaft, and a wringer supporting member, said wringer supporting member and the elements of the driving gear being mounted wholly on one of the side frame members 40 and removable therewith as a unit.

10. In a driving gear for washing machines, a supporting frame comprising two side frame members, a washing receptacle mounted between said side frame members, 45 a wringer, driving means for said washing receptacle, driving means for said wringer, and a main driving mechanism common to both the driving means of the washing receptacle and the driving means of 50 the wringer, said main driving mechanism being supported wholly on one of the said side frame members, and the driving means for the washing receptacle, and the driving means for the wringer being like- 55 wise mounted upon the same side frame member.

In testimony whereof I affix my signature.

JAMES L. COFFIELD.
